UNITED STATES PATENT OFFICE.

GEORGE W. WELLS, OF AMESBURY, MASSACHUSETTS, ASSIGNOR TO WALKER WELLS COMPANY, OF AMESBURY, MASSACHUSETTS, A CORPORATION OF MASSACHUSETTS.

COWL-VENTILATOR FOR MOTOR-VEHICLES.

1,374,696.

Specification of Letters Patent. Patented Apr. 12, 1921.

Application filed August 5, 1920. Serial No. 401,364.

To all whom it may concern:

Be it known that I, GEORGE W. WELLS, a citizen of the United States, resident of Amesbury, in the county of Essex and State 5 of Massachusetts, have made a certain new and useful Invention in Cowl-Ventilators for Motor-Vehicles; and I declare the following to be a full, clear, and exact description of the same, such as will enable others 10 skilled in the art to which it appertains to make and use the invention, reference being had to the accompanying drawings, and to letters or figures of reference marked thereon, which form a part of this specification.

15 Figure 1 is a perspective view of the invention as applied.

Fig. 2 is a central vertical section of the same.

Fig. 3 is a bottom plan view of the same.

20 Fig. 4 is a section on the line 4—4 Fig. 3.

Fig. 5 is an enlarged sectional detail view of the hinge.

Fig. 6 is a detail perspective view of the clamp device.

25 The invention relates to a cowl ventilator for motor vehicles, and it consists in the novel construction and combinations of parts as hereinafter set forth.

In the accompanying drawings illustrating the invention, the numeral 2 designates 30 the cowl, the top of which is provided with an elongated opening 3, wherein is seated a metal lining 4, provided with rear notches 6, open at their lower ends, and with rear 35 perforated lugs 7, said notches extending upwardly to said lugs. The lining is provided with a flange 4' which rests upon the top of the cowl, and the lugs 7 are located beneath and concealed by said flange.

40 Fitting over the opening 3 is a cover 8, having a downturned marginal flange engaging the upturned flange 9, of said lining, the cover being provided with a downward extension 10, and bolted or screwed to 45 this extension at 11, 11, is a hinge casting 12, having rearwardly projecting lugs 13, engaging the notches 6, and provided with perforations in line with those of the lugs 7, a hinge rod 14, engaging the aligned perforations. The hinge casting is also provided with a central downward extension 15, projecting below the lugs 13 and below 50 the top of the cowl.

Connecting the front and rear walls 16

and 17 of the cowl is a rod 18, having at 55 one end engagement with a seat 19 of the rear wall 16, and at its other end passing through a perforation 20 of the front wall 17, a nut 21 being threaded on the terminal portion of said rod and engaging the outer 60 face of said wall, and a lock nut 22 being threaded on the rod and engaging the inner face of said wall.

Engaging the rod 18 is a securing or clamp device 23, of spring strap metal, and 65 provided with an upper eye 24, formed by bending the strap metal blank centrally thereof, said blank being then bent outwardly to form shoulders 25, and then downwardly to form oblique diverging branches 26, 70 the latter having perforations 27, which are slightly elliptical or elongated and through which the rod 18 passes. The eye 24 and the lower end of the extension 15, are connected by a rod 28, pivotal screw bolts 29 75 and 30 being the medium of connection.

The tendency of the branches 26, to spring 80 farther apart or outwardly through their inherent elasticity causes the upper and lower portions of the marginal walls of the 85 perforations 27, to bind frictionally against the rod 18, to thereby secure the clamp device against movement slidably along said rod and also secure the cover 8 in position as adjusted to raised or other position.

In operation, the branches of the clamp device are pressed together to release the frictional bind of the upper and lower portions of the marginal walls of the perforations 27 against the rod 18, after which the 90 clamp device can be moved slidably along the rod to raise the cover to any suitable or desired degree or to lower the previously raised cover, the branches 26 being then released and automatically springing back to 95 normal position in frictional engagement with said rod to hold the adjustment.

In this adjustment or movement, the extension 15 of the cover acts as a lever and forms with the rod 28 a joint of the nature 100 of a knee or toggle joint. The result is that the clamp device is readily operable for the purpose stated and a given movement thereof causes a considerably greater opening or closing movement of the cover.

105 I claim:

1. In a cowl ventilator for motor vehicles, a cowl having a ventilating opening in the

top thereof, a hinged cover for said opening, a stationary rod, a spring clamp bent centrally to provide an upper eye and having diverging spring branches provided 5 with perforations engaging said rod, and adjustable along and automatically gripping said rod, a shaft carried in said eye, and an operating connection between said shaft and said cover to raise and lower the 10 cover upon adjustment of the clamp and to support the cover in raised position.

2. In a cowl ventilator for motor vehicles, a cowl having a ventilating opening in the top thereof, a lining for said opening 15 having a flange engaging the top of the cowl and hinge lugs located beneath said flange, a cover for said opening having hinge lugs pivotally connected with the first named lugs, a stationary rod, a spring clamp ad- 20 justable along and automatically gripping said rod, a shaft carried by said clamp, and

an operating connection between said shaft and said cover.

3. In a cowl ventilator for motor vehicles, a cowl having a ventilating opening in the 25 top thereof, a lining for said opening, having a flange engaging the top of the cowl and hinge lugs located beneath said flange and slots extending upwardly to said hinge lugs, a cover for said opening having hinge 30 lugs movable in said slots and pivotally connected with the first named lugs, a stationary rod, a spring clamp adjustable along and automatically gripping said rod, a shaft carried by said clamp, and an operating 35 connection between said shaft and said cover.

In testimony whereof I affix my signature in presence of two witnesses.

GEORGE W. WELLS.
